Primary Examiner — Omeed Agilee(74) *Attorney, Agent, or Firm* — Warner Norcross + Judd LLP(57) **CLAIM**

The ornamental design for an emergency cot side rail, as shown and described.

DESCRIPTION

FIG. 1 is a back perspective view of an emergency cot side rail;

FIG. 2 is a front perspective view thereof;

FIG. 3 is another back perspective view thereof;

FIG. 4 is a bottom plan view thereof;

FIG. 5 is a top plan view thereof;

FIG. 6 is a right side elevation view thereof; and,

FIG. 7 is a left side elevation view thereof.

The broken lines immediately adjacent to the solid lines depict boundaries of the claimed design and form no part thereof.
